ELECTRIC ALARM SIGNALING SYSTEM

Egil Cohrt, Copenhagen, Denmark, assignor to
International Standard Electric Corporation,
New York, N. Y., a corporation of Delaware

Application May 1, 1943, Serial No. 485,405
In Denmark July 13, 1940

7 Claims. (Cl. 179—5)

1

The present invention relates to a telephone system, containing means for establishing a connection from an exchange to a plurality of subscribers simultaneously, for instance by alarm, and one object of the invention is to provide such a telephone system, which is reliable and simple, and in which it is possible to converse from an exchange over the telephone with each of the subscribers, and the subscribers or certain groups of subscribers may be called simultaneously.

Another object of the invention is to provide a telephone system applicable, for instance, to a fire alarm system in a smaller town, where the firemen are not constantly on duty at the fire-station, but the latter is provided with a telephone command-station from which lines extend to the private homes of the firemen so that any individual line may be chosen for conversation with a selected fireman, or alarm calls may be made to a selected group of firemen or to all the firemen simultaneously.

These and other objects are accomplished, according to the invention, by the arrangement and combination of elements set forth in the following description, defined in the appended claims and illustratively exemplified in the accompanying drawings, in which

Fig. 1 is a circuit diagram for a command-station;

Fig. 2 is a diagram of a distributing circuit common to a group of subscribers;

Fig. 3 is a diagram of a subscriber's line circuit;

Fig. 4 is a diagram of a common circuit serving all the subscribers; and

Fig. 4a is a diagram of a further circuit serving a group of subscribers.

Fig. 5 is a diagram of a circuit for a subscriber's telephone.

Operation of the system in general

The drawing shows an alarm system for the transmission of telephone messages from a command-station at a fire-station to a maximum of thirty firemen at their private homes. The system permits ordinary telephone conversation between the command-station and the firemen singly, whereas conversation between the firemen is impossible. No calls can be made from the firemen. At alarm, which may be made either in groups with a maximum of eight firemen to a group or as general alarm, the firemen cannot talk to the command-station, but acknowledge receipt of the message by depressing a key on their telephone.

2

The subscriber telephones are connected to the command-station through direct lines.

Ordinary telephone conversation

5 A talking key TN, Fig. 1, corresponding to the wanted line, e. g. TN₁, is depressed, whereby automatic ringing, i. e. about 2 seconds ringing takes place about every fifth second and a corresponding call back signal is sent to the telephone apparatus 10 of the command-station.

When the called subscriber answers, the ringing and the call back signal cease, and an answer lamp SL, indicating that the connection has been established, is lighted whereupon the conversation 15 may take place.

When the conversation is finished, the key TN is restored, whereupon the connection is interrupted. It should be noted that when the lamp SL has once been lighted, it remains illuminated 20 until the corresponding key TN has been restored.

Alarm

One or more group keys GN, or in case of general alarm, a general alarm key GAN is depressed, whereupon automatic ringing is sent out to all the corresponding lines.

In order to distinguish between alarm and ordinary calls, the ringing consists in the case of alarm of two double ringings each lasting about 30 $\frac{1}{2}$ second every fifth second.

An amplifier is inserted between the telephone apparatus of the command-station and the relay equipment.

When the various firemen answer, the corresponding lamps SL are lighted, and the message may be given. It is not necessary that all the firemen have answered before the message is sent, the ringing being continued on the other lines which are automatically connected to the 40 command-station as they answer.

The firemen acknowledge receipt of the message by depressing an acknowledge key KN on their telephone apparatus, whereby a corresponding acknowledge lamp KL is lighted on the command-station.

When the keys GN or GAN are restored all the relays are released, and the command-station may make a new alarm.

50 *Detailed description of the operation at an ordinary telephone conversation*

If the operator at the fire-station wants to talk to a certain fireman, the individual talking key corresponding to this fireman's line, e. g. key 55 TN₁, is depressed, whereby earth is connected

to battery over the winding of a corresponding calling relay Str_1 and also across the slow working right middle back contact of this relay over the winding of a ringing relay Rcr_1 , and the latter is energized before the relay Str_1 has interrupted said back contact.

Relay Rcr_1 is locked over a separate winding and its right inner front contact to battery on relay Str_1 's fast working outermost right front contact which is closed before the slow working back contact is interrupted. Relay Str_1 connects earth to the charging circuit (not shown) so that charging of the battery is interrupted during the conversation.

As all the keys TN are connected in series, it will be seen that these keys cannot be used to energize two or more calling relays Str simultaneously, so that connection between two different fireman's lines is prevented.

Ringing

Over the outermost left front contacts of each of the relays Str and Rcr , a circuit is closed for a common relay Rsr which starts the ringing machine RM and further connects earth to the winding of a relay Ipr_1 via the back contact of a relay Ipr_2 . Upon energization of the relay Ipr_1 a circuit is closed for the relay Ipr_2 which attracts slowly in order to give relay Ipr_1 time for being saturated, as this relay is to release slowly when relay Ipr_2 interrupts its back contact. Over the front contact of relay Ipr_2 a circuit is closed for the magnet SM of a step by step selector, and the magnet armature is attracted. When relay Ipr_1 is deenergized, it interrupts the circuit for relay Ipr_2 which breaks the circuit for the magnet SM . The armature of SM releases and the step by step selector advances one step. When relay Ipr_2 closes its back contact, relay Ipr_1 is energized again, and the same cycle is repeated so that the step by step selector advances step by step and stops $\frac{1}{4}$ second on each contact, as long as relay Rsr remains energized over the front contacts of any relay pair Str , Rcr .

At the outermost right back contact of a converter relay For , earth is connected to the b brush of the step by step selector, so that a ringing transmitter relay Rr is energized while the step by step selector SM passes its bank contacts **2** to **7**. Ringing is sent to the selected line in the following circuit: source of ringing current RM , individual ringing lamp RL_1 , a front contact of the common ringing transmitter relay Rr , right middle back contact of an individual alarm relay $Gari$, left outermost front contact of the energized ringing relay Rcr_1 , 180 ohms winding on an individual answer relay Br_1 , a wire L_2 , a bell in the telephone apparatus, a wire L_1 , right middle front contact of the relay Rcr_1 and to earth. The answer relay Br_1 in the ringing circuit remains deenergized as long as this circuit is closed over the bell in the subscriber's telephone.

Two seconds ringing is thus given every fifth second until an answer is received or until the key TN_1 is restored.

Call back signal is sent to the telephone apparatus of the command-station over a call back circuit connecting the main line and its telephone apparatus to the ringing circuit through the inner front contacts of relay Str_1 , a $\frac{1}{30}$ MF condenser and the outermost right front contact of the ringing relay Rcr_1 .

Answer

When the called fireman removes the receiver

from the cradle, a loop is closed through the telephone apparatus so that the answer relay Br_1 , which is shunted by a 500 ohms resistance over the innermost left front contact of relay Rcr_1 , is energized and interrupts the locking circuit for relay Rcr_1 which releases. If an answer arrives during a ringing, the answer relay Br_1 is energized from battery in series with the ringing machine, but if an answer arrives in an interval between two ringings, the relay Br_1 is energized from battery on the back contact of the ringing transmitter relay Rr .

The release of the ringing relay Rcr_1 puts the line through to the command-station through two condensers and interrupts the call back signal. The telephone apparatus of the command-station receives microphone current from an induction coil RC , whereas the connected subscriber apparatus receives microphone current through the answer relay Br_1 in the following circuit: earth, left innermost back contact of the corresponding alarm relay $Gari$, left 180 ohms winding on relay Br_1 , right back contact on relay Rcr_1 , the wire L_1 , the telephone apparatus, the wire L_2 , right 180 ohms winding on relay Br_1 , outermost left back contact on relay Rcr_1 , outermost left front contact on relay Str_1 and to battery.

Answer relay Br_1 , which is now energized in the above mentioned circuit, closes a circuit for the repeater relay Kvr_1 , which is energized slowly and makes battery connection over the left outermost back contact of the alarm relay $Gari$ to the lamp SL_1 which is lighted and thereby indicates that an answer has been given.

When the relay Rcr_1 is released, the circuit for the common relay Rsr is interrupted, and this relay releases and interrupts the circuits for the relays Ipr_1 , Ipr_2 and Rr which all release.

From the outermost left back contact of relay Rsr earth is then connected to the contacts in the contact bank a and through the brush a and the magnet of the step by step selector is energized over the break contact of the latter, whereby its armature is attracted. Immediately thereafter, the break contact interrupts the circuit so that the armature is released and the step by step selector advances one step, after which the break contact is closed again. The step by step selector moves to normal position where the magnetization circuit is definitely interrupted.

Release

When the conversation is finished the key TN_1 is restored so that relay Str_1 is released together with the relays Br_1 and Kvr_1 , after which all the relays are again in their normal positions.

Alarm

At alarm, one or more of the group keys GN , $a-e$ or, in case of a general alarm, the general alarm key GAN is depressed.

A group calling relay Gur , $a-e$ corresponds to each key GN , $a-e$, respectively, and controls a group of at most eight lines.

Upon depression of the general alarm key GAN , all the group calling relays Gur , $a-e$ are simultaneously energized.

In each line circuit of the called groups an alarm relay Gar is energized, and, over the middle left front contact of this relay, a circuit is closed for the relays Str and Rcr of the selected group in the same way as if the corresponding keys TN had been depressed. The relays Rcr are locked and cause transmission of ringing current.

The common converter relay For is energized

by a circuit from earth over the keys GN or GAN and inserts an amplifier (not shown) which is started from one of its front contacts.

Ringing

When an alarm relay, e. g. Gari, is energized the call back circuit is interrupted at the outermost right back contact of this relay Gari, and the ringing itself is derived over the middle right front contact of the latter.

The relay Rsr in the common circuit is energized, and the step by step selector advances step by step as already explained, but since the converter relay For is energized there is earth on the brush c instead of on the brush b.

In order to decrease the load on the ringing machine the ringing contacts for the various groups in the c bank are displaced relative to each other, so that ringing is made to one group only at a time. In case of group a, for instance, a group ringing relay Grra is energized from the contacts 1—2 and 5—6 of selector bank c whereby double ringing is made about every fifth second.

Answer

As each fireman of the group called takes off his receiver, the corresponding answer relay Br is energized as mentioned and interrupts the locking circuit for the associated ringing relay Rcr which releases, but the relay Br cannot remain energized, because battery is now connected to its left winding from the innermost left front contact of the associated relay Gar. Each relay Br is therefore released again before the corresponding repeater relay Kvr has had time to operate.

As both of the windings of the answer relay Br are now connected to battery, no microphone current is supplied to the subscriber apparatus so that it is not possible to talk from it and thereby disturb the message.

The answer lamp SL is lighted over the outermost left hand front contact of the relay Str and the back contacts of relays Rcr and Br and indicates thereby that the fireman is ready to receive the message which is sent from the command-station by means of the amplifier.

The two 200 ohms resistances inserted in the talking line serve for preventing disturbances, for instance from a short-circuited line.

Acknowledgement

When the message has been received the fireman acknowledges the receipt by depressing for a moment an acknowledge key KN of his telephone apparatus, whereby earth through an induction coil is connected to the wire L1 and energizes the corresponding answer relay Bri through its left winding. The repeater relay Kvr1 is energized from the front contact of relay Bri and is locked over the innermost right front contact of relay Gar1, as relay Bri is again released when the key KN is restored. Relay Kvr1 connects battery to the acknowledge lamp KL1 which is lighted at the command-station.

When all the firemen have acknowledged the receipt of the message, the key or keys GN, or possibly the key GAN, are restored, and all energized relays are released, after which the system is ready for another alarm.

I claim:

1. In a telephone system with alarm device having a command-station, a telephone at said command-station, a two wire main line connected to said telephone at said command-station, a plurality of two wire subscriber lines and a plurality

of subscriber telephones each including a bell circuit connected across the associated subscriber's line when said subscriber's telephone is in its inoperative position and a microphone circuit substituted for said bell circuit across said subscriber's line when said subscriber's telephone assumes its operative position, the combination of a calling circuit for each individual subscriber, individual talking keys at said command-station to close each of said calling circuits, a calling relay in each of said calling circuits to connect, upon being energized, the called subscriber's line to the main line, a ringing machine common to all subscribers, a ringing circuit for each subscriber adapted to be connected to said common ringing machine, an answer relay for each subscriber, a ringing relay for each subscriber, an energizing circuit for each ringing relay including a slow working back contact of said calling relay, a stick circuit for each ringing relay containing a back contact of the corresponding answer relay and a fast working front contact of said calling relay, said ringing relay being adapted to break the subscriber's line intermediate said calling relay and the subscriber's telephone and to connect said ringing circuit through a winding of the answer relay to the part of the subscriber's line connected to said telephone, each answer relay being adapted to remain deenergized when a circuit through its winding is closed over the corresponding bell circuit and to become energized when it is traversed by current flowing through the subscriber's microphone circuit, a source of microphone current for each subscriber's telephone, a microphone current circuit connecting said source of microphone current across the corresponding subscriber's line over a winding of said answer relay, a back contact of the ringing relay and a front contact of the calling relay, a number of group keys at said command-station, a number of group calling relays each energized upon operation of the corresponding group key to close a predetermined group of calling circuits, and an alarm relay for each subscriber energized over a front contact of the corresponding group calling relay, each alarm relay having a back contact inserted in the corresponding microphone current circuit.

2. A system, as claimed in claim 1, including for each subscriber a call back circuit connecting the main line in parallel with the selected subscriber's telephone and in series with a winding of said answer relay to the selected ringing circuit over front contacts of the corresponding calling and ringing relays and at least one back contact of the corresponding alarm relay.

3. A system, as claimed in claim 1, including, at said command-station, an answer signal for each subscriber, and means to energize each answer signal alternatively over a front contact of the corresponding calling relay and back contacts of the corresponding ringing relay and answer relay when the latter is deenergized or over a back contact of the corresponding alarm relay when said answer relay has been energized for a predetermined length of time.

4. A system, as claimed in claim 1, including a general alarm key at the command-station to energize all said group calling relays simultaneously.

5. A system, as claimed in claim 1, comprising a common converter relay, means to energize said converter relay upon actuation of any of said group keys, an amplifier, and means controlled

by said converter relay to insert said amplifier into said main line.

6. A system, as claimed in claim 1, including a step by step selector having a first and a second brush and associated contact banks, means for rotating said step by step selector as long as a ringing relay is energized, a common ringing transmitter relay connected to a selected contact group of said first bank, a separate group ringing relay for each group of subscribers, each group ringing relay being connected to a different selected contact group of said second bank, a converter relay, means to energize said converter relay upon actuation of any of said group keys, a circuit for intermittent energization of said ringing transmitter relay over said contact group in said first bank, the first brush and a back contact of said converter relay, and circuits for intermittent and successive energization of said group ringing relays over the corresponding contact groups of said second bank, said second brush and a front contact of said converter relay, each of said ringing circuits being connected with said ringing machine selectively over a front contact of said ringing transmitter relay and a back contact of the corresponding alarm relay or over a front contact of the associated group ringing relay and a front contact of the corresponding alarm relay.

7. A system, as claimed in claim 1, including, in each subscriber's telephone, an acknowledge key adapted to close an energizing circuit for said answer relay over one wire of the associated subscriber's line, a back contact of the associated ringing relay and a front contact of the associated alarm relay, an acknowledge signal for each subscriber at said command-station, and means to actuate each acknowledge signal over a front contact of the associated alarm signal when said answer relay has been energized for a predetermined length of time.
